E. J. OLSEN.
BED RAIL JOINT.
APPLICATION FILED DEC. 11, 1911.

1,031,660.

Patented July 2, 1912.

UNITED STATES PATENT OFFICE.

EINAR J. OLSEN, OF MINNEAPOLIS, MINNESOTA, ASSIGNOR OF ONE-FOURTH TO
GEORGE GROSCHEN, OF MINNEAPOLIS, MINNESOTA.

BED-RAIL JOINT.

1,031,660.

Specification of Letters Patent.

Patented July 2, 1912.

Application filed December 11, 1911. Serial No. 664,990.

To all whom it may concern:

Be it known that I, EINAR J. OLSEN, a citizen of the United States, residing at Minneapolis, in the county of Hennepin and 5 State of Minnesota, have invented certain new and useful Improvements in Bed-Rail Joints; and I do hereby declare the following to be a full, clear, and exact description of the invention, such as will enable others 10 skilled in the art to which it appertains to make and use the same.

My invention has for its object to provide an improved bed rail joint and, to this end, the invention consists of the novel devices 15 and combinations of devices hereinafter described and defined in the claims.

The invention is illustrated in the accompanying drawings, wherein like characters indicate like parts throughout the several 20 views.

Referring to the drawings, Figure 1 is a plan view of the improved joint applied to a bed post and side rail; Fig. 2 is an outside side elevation of the parts shown in Fig. 1; 25 Fig. 3 is a longitudinal section taken on the line $x^3 x^3$ of Fig. 1; Fig. 4 is a transverse section taken on the line $x^4 x^4$ of Fig. 3, with some parts removed; Fig. 5 is a vertical section taken on the line $x^5 x^5$ of Fig. 1; Fig. 6 30 is a view partly in transverse vertical section on the line $x^6 x^6$ of Fig. 1, with some parts shown in full; Fig. 7 is a side elevation of the parts shown in Fig. 6; and Fig. 8 is a detail in section on the line $x^8 x^8$ of 35 Fig. 1.

The numerals 1 and 2 indicate, respectively, a portion of a bed post and a portion of one of the side rails detachably connected by means of my improved bed rail joint.

40 The improved bed rail joint comprises an inner coupling head 3, detachably secured to the bed post 1, and an outer coupling head 4, secured to the side rail 2 by means of rivets or otherwise. The inner coupling head 3 is made hollow and comprises pairs 45 of oppositely projecting upper and lower bearing shoulders 5 and 6, respectively, and a wedge-like flange 7. The upper and lower bearing shoulders 5 and 6 on opposite sides 50 of the coupling head 3, are vertically aligned, as best shown in Fig. 7. And the wedge-like flange 7 is formed by contracting the coupling head 3 forward of the bearing shoulders 5 and 6 and is located immediately therebetween, as best shown in Figs. 1 and 4. This wedge-like flange 7 is tapered from its bottom toward the upper bearing shoulders 5, the purpose of which will presently appear.

1 and 4. The coupling head 3 is vertically divided 60 intermediately between the upper and lower bearing lugs 5 and 6 and centrally through the wedge-like flange 7. A pair of clamping prongs 8 are integrally formed, one on each member of the divided coupling head 65 3 and extend rearwardly from the bearing shoulders 5 and 6. These clamping prongs 8 embrace the bed post 1 and are curved to approximately fit the outer diameter thereof, as best shown in Figs. 1 and 4. It will 70 be noted that these prongs 8 are so arranged as to hold the two members of the clamping head 3 slightly spaced apart at their inner surfaces and adjacent to the bed post 1. And it will also be noted that the free vertical edges of the prongs 8 are spaced apart. 75 This spacing of the members of the clamping head 3 and the prongs 8, is necessary in order to permit the clamping prongs 8 to be clamped onto the bed post 1, by means 80 that will presently be described.

On the inner faces of the clamping prongs 8 are formed, a pair of oppositely and inwardly projecting, tapered lugs 9. These lugs 9 are adapted to be inserted through 85 diametrically opposite seats 10 drilled on opposite sides of the bed post 1. It will be noted that these seats 10 are of slightly larger diameter than the lugs 9. As is evident, these tapered lugs 9 and coöperating 90 seats 10 tend to hold the clamping head 3 properly vertically spaced in respect to the bed post 1. By reference to Figs. 3 and 4, it will be noted that the lugs 9 are so arranged with respect to the seats 10, that 95 when the prongs 8 are clamped onto the bed post 1, the lugs 9 are drawn into engagement with the inner faces of the seats 10, thereby preventing any tendency of the coupling head 3 to rotate, with respect to 100 the bed post 1.

The two members of the clamping head 3 are held interlocked against vertical movement, with respect to each other, by means of a lug 11 and a coöperating seat 12 formed 105 on the inner vertical faces of the flange 7. For holding the two members of the clamping head 3 together and for clamping the prongs 8 onto the bed post 1, a nut equipped draw-bolt 13 is passed through seats in said 110

members of the clamping head 3. Integrally formed on the inner member of the clamping head 3, is an inwardly and horizontally projecting lug 14 to which is secured, by screw bolts or otherwise, a tie bar 15 which connects opposite bed posts.

The coupling head 4 is bifurcated and the prongs 16 thereof have their ends bent laterally inward to form, vertically extended, bearing lugs 17 for coöperation with the bearing shoulders 5 and 6. The inner faces of the prongs 16, adjacent to their crotch, are reversely curved both vertically and horizontally to form raised bearing surfaces 18 adapted to engage opposite surfaces of the wedge-like flange 7, as best shown in Figs. 1 and 8. As is evident, the wedge acting flange 7 acting on the bearing surfaces 18 tends to draw the bearing lugs 17 onto the bearing shoulders 5 and 6.

From the foregoing description, it will be noted that each prong 16 and its bearing lug 17 has a three-point contact with each member of the coupling head 3, as best shown in Figs. 1, 7, and 8, and further, by this arrangement, the two members of the coupling head 3 are held interlocked, one with the other, and their clamping prongs 8 are held securely clamped onto the bed post 1. It is evident that in case the bolt 13 becomes loose or entirely removed from the coupling head 3, the interlocking engagement of the coupling heads 3 and 4, together with the coöperating lugs 9, will securely hold the prongs 8 clamped onto the bed post 1. This three-point interlocking engagement of the coupling heads 3 and 4 securely holds the coupling heads interlocked against lateral or vertical movements, with respect to each other, and, by this interlocking arrangement of the coupling heads, the castings comprising the coupling heads 3 and 4 need not be very smooth, as any unevenness therein, would not affect the interlocking engagement thereon.

The above described device, while extremely simple and of comparatively small cost, has, in actual practice, been found highly efficient for the purpose had in view.

50 What I claim is:

1. The combination with a bed post and a bed rail, of a divided coupling head having clamping prongs, said prongs arranged to

embrace the bed post and having interlocking engagement therewith, and a second 55 coupling head applied to the bed rail, embracing said divided coupling head and operative thereon to hold the prongs thereof interlocked with the bed post.

2. The combination with a bed post and 60 a bed rail, of a divided coupling head having clamping prongs arranged to embrace the bed post, lugs on said prongs and insertible in seats in said bed post, and a second coupling head applied to the bed rail, 65 embracing said divided coupling head and operative thereon to hold the prongs thereof interlocked with the bed post.

3. The combination with a bed post and 70 a bed rail, of a divided coupling head having clamping prongs arranged to embrace the bed post, the members of said divided coupling head having interlocking engagement with each other, lugs on said prongs and insertible in seats in said bed post, and 75 a second coupling head applied to the bed rail, embracing said divided coupling head and operative thereon to hold the prongs thereof interlocked with the bed post.

4. The combination with a bed post and 80 a bed rail, of a divided coupling head having clamping prongs arranged to embrace the bed post, the members of said divided coupling head having interlocking engagement with each other, lugs on said prongs 85 and insertible in seats in said bed post, a draw bolt operative on the members of said divided coupling head for clamping their prongs onto the bed post, and a second coupling head applied to the bed rail and having 90 interlocking engagement with said divided coupling head.

5. The combination with a bed post and 95 a bed rail, of a divided coupling head having clamping prongs embracing the bed post, and a second coupling head applied to the bed rail and having three-point contact with each member of said divided coupling head, for clamping the prongs thereof onto the bed post.

In testimony whereof I affix my signature in presence of two witnesses.

100 EINAR J. OLSEN.
